UNITED STATES PATENT OFFICE.

EDWIN C. WORNS, OF NEW YORK, N. Y.

COMBINED MOP HEAD AND WRINGER.

1,161,104.

Specification of Letters Patent. Patented Nov. 23, 1915.

Application filed April 16, 1915. Serial No. 21,658.

To all whom it may concern:

Be it known that I, EDWIN C. WORNS, a citizen of the United States, and a resident of the city of New York, borough of Manhattan, in the county of New York and State of New York, have invented a new and Improved Combined Mop Head and Wringer, of which the following is a full, clear, and exact description.

10 My present invention relates to mops having means for wringing the mop cloth through the medium of gearing, and the invention more particularly relates to the mop forming the subject of application for 15 Letters Patent filed by me May 2, 1913, Serial No. 765,082. In my above named application a presser frame is connected to the handle and is formed with a front loop for the mop cloth; a second loop for the rear 20 end of the mop cloth is mounted to turn on the handle, and is geared to a sector having a lever handle which normally projects forwardly over the rear loop and the presser frame and is permitted a rearward and upward movement to turn the said rear loop 25 and wring the mop.

The present invention provides a novel form and arrangement of the sector relative to the co-acting gear element of the twisting loop, whereby the intermeshing gear teeth will be held to their work and will resist the tendency to separate under the severe strain exerted thereon by the twisting of the mop cloth.

30 Other important features of the invention will appear from the following description.

Reference is had to the accompanying drawings forming part of this specification, 40 in which similar characters of reference indicate corresponding parts in all the views, and in which:

Figure 1 is a plan view of the mop embodying my invention; Fig. 2 is a side elevation; and Fig. 3 is a detail inverted plan view, largely diagrammatic, given to show the special sector and its relation to the co-acting gear element.

In the illustrated practical embodiment 50 of my invention, a handle member 10, in the form of a socket, receives a detachable handle 11. Projecting forwardly from the handle 10 is an arched arm 12 having at its forward end a hub 13 which is received 55 between spaced ears 14 on the presser frame 15. The connection is effected by a bolt 16

passing through said hub 13 and ears 14 and a suitable nut 17 on the bolt. The frame 15 presents a front loop 18 having a cross-bar 19 and from the said loop a slot 60 15 extends rearwardly and through the rear end of the said frame, thereby separating the latter into two side members having respectively the ears 14. There are preferably two pairs of ears 14 to permit the connection of the handle at different points on the presser frame 15.

A twisting loop 20 is provided to receive the rear end of the mop cloth 21 and mounted to turn in a bearing 22 on the handle member 10 and provided with a beveled spur pinion 23 which meshes with teeth 25 on a sector 24, said sector being mounted to rock on the handle member 10 by means of a bolt 26, or equivalent means. The sector 24 has 75 a lever handle 27 rigid therewith disposed generally in a radial direction, or approximately so, and the arrangement is such that when the mop 21 is in the untwisted form so as to lie flat beneath the presser frame 21 80 for use in mopping, the handle 27 will extend forwardly over the twisted loop 21 and overlap the rear end of the presser frame 15, whereby an upward and rearward throw of the lever handle from the forward 85 position toward and adjacent to the handle 11 will effect a wringing of the mop cloth.

In the use of the mop on a wall or ceiling, the tightening of the nut 17 will serve to effect the rigid adjustment of the presser frame 15 in the desired angular position. When the mop is used on a floor, the presser frame 15 is loosely pivoted and as the front end overbalances the heel, the heel of the frame when the mop is lifted from the floor 95 will be tilted upwardly and will engage the lever handle 27 raising the same sufficiently to permit the convenient grasping of said handle for the twisting of the mop cloth. The raised position of the lever handle and 100 the tilted position of the heel of the presser frame 15 are indicated in dotted lines in Fig. 2, the full lines indicating the normal position, in which it will be seen that the lever handle 27 at its forward end lies close 105 to the presser frame, so that the device can be conveniently entered beneath an ice-box or other structure or article of furniture.

In order to limit the tilting movement of the presser frame 15 when loosely pivoted, 110 I form on the arm 12 adjacent to the hub 13 thereof, lateral lugs 28 which overlap

the lugs 14 of the presser frame at each side of the slot 15^a, and on the presser frame 15 adjacent to the forward lugs 14 I provide raised members 29, the lugs 28 projecting into the path of movement of the the said members 29 in the rocking of the presser frame and serving to arrest the movement of the latter. Similar lugs or raised members 29^a are provided behind the rear lugs 14 on the presser frame.

The construction and arrangement of the parts is such that a throw of the lever handle 27 from the forward position to a position adjacent to the handle 11, will effect a wringing of the mop cloth, and the final twists imparted to the mop cloth will be given with facility by grasping both the handle 11 and the lever handle 27. In order to hold the said gear elements to their work and prevent separation of the teeth under the strain of wringing, I so form and arrange the sector relative to the pinion, that the teeth 25 thereon (see Fig. 3) will be spirally disposed. In Fig. 3 I have indicated a line A parallel to the axis of the pinion 22. It will be observed that the teeth 25, from the end of the sector adjacent to the lever handle, are disposed a gradually decreasing distance from the axial line of the pinion. Thus the separating strain will be resisted and compensated for, since in the turning of the sector, the teeth thereof will gradually project an increasing distance toward the axis of the pinion to insure a firm engagement with the pinion.

It is important that the twisting loop 20 be arranged approximately horizontal beneath the lever handle 27 when the mop cloth is flat and untwisted, and this is insured by a proper engagement of the sector with the pinion 23. In order to prevent the throwing of the handle 27 to a position to completely disengage the sector from the pinion, and thus permit a wrong relation to be established in again engaging the sector with the pinion, I provide a stop tooth 25^a on the sector, of a depth to lock with the pinion 22 should undue movement be given to the lever 27. In this way the proper relation of the sector and the pinion is insured after the article has reached the hands of the purchaser.

Having thus described my invention, what I claim as new and desire to secure by Letters Patent, is:

1. In a mop, a presser frame, a handle member connected with said frame and having a front loop to receive a mop cloth, a twisting loop mounted to turn and adapt-

ed to receive the rear end of the mop cloth, 60 and means to turn the said twisting loop, said means comprising a pinion on the twisting loop, and a toothed sector mounted to rock on the handle and meshing with the said pinion, the sector having a lever handle 65 projecting forwardly therefrom to rock the sector and to turn the mop by a rearward and upward throw of the lever handle, the teeth on the sector being spirally disposed, the teeth from the end of the sector 70 adjacent to the lever handle being disposed a gradually decreasing distance from the axial line of the pinion.

2. In a mop, a handle member, means on said handle member to hold the front end 75 of a mop cloth, a twisting loop mounted to turn on the handle and adapted to receive the rear end of a mop cloth, and means to turn the twisting loop, said means comprising a pinion on the twisting loop, and a sector, said sector having a spiral series of 80 teeth meshing with the pinion.

3. In a mop, a handle member, means on the said handle member to hold the front 85 end of the mop cloth, a twisting loop mounted to turn on the handle and adapted to receive the rear end of a mop cloth, and means to turn the twisting loop, said means comprising a pinion on the twisting loop, and a sector having teeth meshing with the 90 pinion, there being a tooth near one end of the sector projecting a sufficient distance to lock with the pinion and prevent movement of the sector beyond the pinion.

4. In a mop, a presser frame comprising 95 a front loop to receive a mop cloth, and having a longitudinal slot extending rearwardly from the said loop through the rear end of the frame, separating the side members of the latter, a handle member 100 having a forwardly extending arm, and means rockably connecting the forward ends of the said arm with the presser frame between the side members thereof, said forward end of the arm having a lateral lug 105 overlapping the adjacent side member of the presser frame, and the said side member having a stop member to contact with the said lug to limit the locking movement of the presser frame on the said arm. 110

In testimony whereof I have signed my name to this specification in the presence of two subscribing witnesses.

EDWIN C. WORNS.
